DESIGN FOR A PLACE MAT OR SIMILAR
ARTICLE

Kenneth C. Hamilton, Milwaukee, Wis., assignor to Milwaukee Lace Paper Company, Milwaukee, Wis., a corporation of Wisconsin

Application March 20, 1947, Serial No. 137,772

Term of patent 14 years

(Cl. D59—2)

To all whom it may concern:

Be it known that I, Kenneth C. Hamilton, a citizen of the United States, residing at Milwaukee, in the county of Milwaukee and State of Wisconsin, have invented a new, original, and ornamental Design for a Place Mat or Similar Article, of which the following is a specification, reference being had to the accompanying drawing, forming a part thereof.

The single figure of the drawing is a face view of a place mat embodying my new design. While my design is shown as delineated on a place mat, it is contemplated that the same may be applied to other similar articles without departing from the spirit of the invention.

I claim:

The ornamental design for a place mat or similar article, substantially as shown and described.

KENNETH C. HAMILTON.
